UNITED STATES PATENT OFFICE.

PETER A. DEASY, OF OAKLAND, CALIFORNIA, ASSIGNOR TO DEASY UTILITIES COMPANY, OF OAKLAND, CALIFORNIA, A CORPORATION.

HEATING SYSTEM.

1,095,559.

Specification of Letters Patent.

Patented May 5, 1914.

Application filed March 6, 1913. Serial No. 752,384.

To all whom it may concern:

Be it known that I, PETER A. DEASY, a citizen of the United States, residing at Oakland, in the county of Alameda and 5 State of California, have invented certain new and useful Improvements in Heating Systems, of which the following is a specification.

This invention relates to heating systems 10 and has as its principal object the construction of a small heating system which may be used in connection with a domestic hot water supply.

Another object is to construct the circulating system so that in case that the radiators 15 are closed the coil will not become overheated.

A further object is to lessen the cost and 20 improve the efficiency of hot water heating systems.

A final object resides in the particular arrangement and combination of parts herein-after described.

The means by which such objects are attained will be fully set forth in the following specification and the attached drawing 25 wherein—

Figure 1 is a view in perspective of a system embodying my invention. Fig. 2 is a 30 section of the lower part of the apparatus shown in Fig. 1.

Denoting corresponding parts by the same numerals of reference, 1 denotes a domestic boiler or tank having the heating coil 2 with 35 a flow pipe 3 and return pipe 4 which latter runs to a point near the top of the boiler where it discharges.

5 denotes the hot water supply pipe leading to the domestic fixtures as at 6.

40 7 denotes the cold water inlet which runs to near the bottom of the boiler in the usual manner.

Outside of coil 2 there is placed a larger coil 8 to which the cold water from the bottom 45 of the boiler is led through pipe 9. From the top of coil 8 pipe 10 leads through an extension 1^a of the wall of the boiler 1 to the vertical riser 11. The latter then connects to branches which are in turn connected to the radiators 12. The return pipe 13 from the radiator is connected to the bottom of the boiler as shown at 14. Intermediate the top and bottom of the boiler an outlet 15 is provided which connects by a relatively 55 small diameter tube 16 with the riser 11.

Above this may be placed a valve 17 which is closed when the heating system is not in use. The usual valves (not shown) will of course be placed at the individual radiators. The coils 2 and 8 are heated by means of a 60 burner 18 which may be of any suitable type, or a grate may be used. The gases from the burner or grate are led through the flue 19 which passes upward through the boiler 1.

The operation of the device is as follows: 65 When the gas burner 18 is lighted, the water in coils 2 and 8 is heated from the former and rises through pipe 4 which opens near the top of the boiler. From the top of coil 8 the water rises through pipes 10 and 11 to 70 the radiator 12 returning to the lower part of the boiler through pipe 13. In case both radiators are turned off the water then has a path to the boiler through the small pipe 16 which is of sufficient size to prevent any 75 pressure rise in coil 8 and yet not large enough to shunt the circulation from pipe 11.

It will be understood by those skilled in the art that while the apparatus shown and described herein is the preferred form of 80 my invention, various modifications thereof may be made without departing from the spirit of my invention.

I claim:

1. A combined hot water supply and heating system comprising in combination, a reservoir tank, a coil for maintaining the temperature of water in said tank, a connection leading from the lower part of said tank to the lower part of said coil, a connection 90 leading from the upper part of said coil to the upper part of said tank, a second coil, a connection leading from the lower part of said tank to the lower part of said second coil, a riser leading from the upper part of 95 said second coil, one or more radiators connected to said riser, a return pipe leading from said radiators to the lower part of the system, and a bypass connected from said riser to said tank. 100

2. A combined hot water supply and heating system comprising in combination, a reservoir tank, a coil for maintaining the temperature of water in said tank, a connection leading from the lower part of said tank to the lower part of said coil, a connection 105 leading from the upper part of said coil to the upper part of said tank, a second coil, a connection leading from the lower part of said tank to the lower part of said second coil, a connection leading from the upper part of said tank to the lower part of said second coil, a connection leading from the lower part of said second coil to the lower part of said tank. 110

coil, a riser leading from the upper part of
said second mentioned coil, one or more
radiators connected to said riser, a return
pipe leading from said radiators to said
5 tank, and a bypass connected from said riser
to said tank.

In testimony whereof I affix my signature
in presence of two witnesses.

PETER A. DEASY.
